The undisclosed side of the urinal shown in the figures is a mirror image of the side shown, and the rear of the urinal is plain.

The dominant features of my design reside in the portions shown in full lines.

I claim:

The ornamental design for a urinal, substantially as shown and described.
